SAMUEL MARANS, OF ATLANTIC CITY, NEW JERSEY, ASSIGNOR OF ONE-HALF TO
CHARLES P. PROFFATT, OF OCEAN CITY, NEW JERSEY.

EMBORESSED-PRINTING MACHINE.

Application filed June 23, 1925. Serial No. 39,084.

This invention relates to machines for producing printing to simulate engraving or embossing, and the said invention has for an object the provision of novel means whereby multicolor printing may be done; the said printing while in a moist state being coated with a powder or granular material which is afterwards subjected to heat after the process well known in the art in which 5 embossing machines are employed.

It is a further object of this invention to produce a printing device of the character indicated in association with a supply of material to be printed, and in which the 15 material is drawn through the printing apparatus in the form of a web; and the said device includes means for imparting motion to the web in a step by step travel, so timed as to permit the printing mechanism 20 to operate successively on the web as it is passed through the printing machine so that multicolored printing can be done when desired, although, of course, the same features may be employed where one color ink is 25 being distributed or used.

Furthermore, it is an object of this invention to provide a coating means through which the web is drawn after it is printed, whereby the printed surface is provided with 30 a deposit of any of the well known or special coatings that are melted or partially melted when subjected to heat, for the purpose of producing the raised or embossed effect; and it is furthermore an object to associate with 35 the last mentioned means an agitator or tapping device which will be operative to dislodge excess deposits of the aforesaid material from the web prior to the time it is subjected to heat, as will presently appear.

It is a still further object of the invention 40 to provide a suitable guide and drawing rollers which pull the web through the printing apparatus and the coating applying means in order that the said web may 45 be delivered to a cutter which will sever the web into appropriate lengths to produce cards of different sizes or sheets of material that have been treated.

It is a still further object of this invention 50 to provide novel means for operating the cutter in time with the drawing rolls and the printing mechanism.

It is a further object of this invention to 55 produce a conveyer and furnace or oven effective to subject the aforesaid treated and

cut sections of the web of stock or material to heat which will be effective to properly heat the cut sections of web and the deposits thereon so that the same will be hardened, as is done in machines of the character mentioned. 60

It is furthermore an object of this invention to produce a heater or oven, through which a conveyer travels for carrying the printed and cut material, and in order that 65 the deposit may be properly baked without injury to the card, or the cardboard (the same to be hereinafter referred to as "cards", the said term being understood to mean any stock in the nature of cardboard, paper or 70 the like bearing the deposits), it has been found in practice that it is desirable to subject the said cards to the action of comparatively intense heat intermittently and to maintain the temperature of the cards in a 75 heated state between the zones of the more intense heat. By the arrangement just stated, the heat is not sufficiently great to impair the cards or scorch them, while at the same time, the deposits are properly heated 80 so that they set and remain hard.

It is a still further object of this invention to produce novel means for regulating the temperature of the oven by the employment of sectional heaters which may be controlled in sections to produce the desired temperatures, and the said heating device, which is in the nature of electrical resistance coils, may be expeditiously and inexpensively repaired, since each resistance element is of short length separately installed. 85

With the foregoing and other objects in view, the invention consists in the details of construction, and in the arrangement and combination of parts to be hereinafter more 90 fully set forth and claimed.

In describing the invention in detail, reference will be had to the accompanying drawings forming part of this application wherein like characters denote corresponding 100 parts in the several views, and in which—

Figure 1 illustrates a view in elevation showing a printing device associated with a coating device;

Figure 2 illustrates a view in elevation of 105 one end thereof;

Figure 3 illustrates a view in elevation of the other end thereof;

Figure 4 illustrates a view in side elevation of a combined heater and conveyer; 110

Figure 5 illustrates a plan view thereof;
Figure 6 illustrates a diagrammatic view of the heating appliance for the oven;

Figure 7 illustrates a perspective view of 5 the card coating device;

Figure 8 illustrates a detail view of the cutter drive; and

Figure 9 illustrates a similar view at an angle to that shown in Fig. 8.

10 In these drawings, 15 denotes a printing press having multicolor distributing rolls 16, 17, 18 and 19 that operate in conventional manner with respect to the type, bed and other parts of a printing press which need 15 not, it is thought, be described in detail.

A bracket 20 rotatably supports a roll 21 of material which is to be cut into appropriate lengths for producing cards after the web 22 has passed through the printing press 20 and through the coating means 23.

The coating device, in the present embodiment of the invention, comprises a box-like structure rectangular in plan, whose end wall 24 terminates above the bottom 25 to produce 25 a slot or opening 26, through which the web is drawn, as will presently appear. A roller 27 is rotatably supported at one side of the device slightly above the bottom in order that the printed web may be drawn through 30 the coating means close to the bottom thereof and under the coating material. The web is then guided through a slot 29 in a guide 30 to the drawing rolls 31 and 32 between which the web travels and from which the 35 web is projected over the stationary knife 33. In order that excess deposits may be removed from the web, a tapper or knocker 34 is oscillatable in the path of travel of the web and it strikes the web intermittently to jar or vibrate it so that excess deposits are removed and descend into the receptacle through which the web has traveled.

The tapper, in the present embodiment of 40 the invention, has a rounded inner end which 45 strikes the web and a tail piece 35 which extends outwardly into the path of rotation of the shoulders 36 of the shaft 37.

The roll 31 has peripheral flanges at its 50 ends in order that the flanges will engage the cards at the edges and straddle the printed surfaces of the cards, whereas the periphery of the roll 32 is plane and supports the card throughout its surface.

The rolls 31 and 32, as well as the shaft 55 37, are geared together by a train 38 in order that they will operate in unison, the roll 32 being positively driven through the pinion 39 and gear wheel 40, which gear wheel 40 is secured on a shaft 41 journaled on a post 60 42 in any suitable manner. The gear wheel 40 is engaged by a dog 43 that is pivoted on an arm 44 carried by a sleeve 45 that is rotatable on a shaft 46, and the action of the dog is controlled by a segmental shield 47 65 having a hub 48 adjustable on the shaft on

which the wheel 40 is secured. As the arm 44 oscillates with respect to the periphery of the gear wheel 40, the wheel engaging nose of the dog will ride over the shield 47 for a suitable distance of its throw, and then engage a tooth of the wheel 40 and impart rotary motion to the said wheel. If the shield 70 47 is positioned to release the dog to engage the wheel early in its movement, the degree of rotation of the wheel 40 will be greater 75 than that when the shield is set to prevent the dog from engaging the wheel 40 so early in its movement, and it is by this arrangement that the degree of movement imparted to the web at each operation of the drawing 80 and cutting mechanism and the size of the card severed from the web is determined, as it will control the length of the feed of the drawing rolls. The hub 48 may be secured to the shaft at different positions of adjustment by any suitable means such as a set screw, as those skilled in the art will understand.

As has been stated, the web is drawn in a step by step motion over the knife 33 and a movable knife 48 operates in conjunction with the stationary knife for cutting the cards. The knife is oscillatable on the shaft 46 in conjunction with a frame which is also oscillatable, and the said frame, in the present embodiment of the invention, consists of arms 49 and 50 which are connected together by a rod 51, and the knife 48 is also connected to the said rod 51. The knife 48 and the arm 49 have projecting trunnions 52 constituting wrist pins on which pitmans or connecting rods 53 operate. The arm 49 has a hub 54 rotatable on the shaft 46 and the arm 50 has the sleeve or hub 45 on its end, the said sleeve 45 and its function having been described, and the knife is carried into an operative relation to the knife 33 as the frame oscillates.

A power shaft 56 is provided with a drive wheel 57 that may have power transmitted 110 to it in any appropriate way, as by a belt, and the said shaft 56 has a pinion 57 secured to it which meshes with a gear wheel 58 on the shaft 59. The shafts 56 and 59 are rotatably supported by posts 60 and 61 and are located a suitable distance rearwardly of the printing mechanism and parts associated with it. The gear wheel 58 has a wrist pin 62 to which an end of a pitman 53 is connected, the wrist pin, of course, being eccentric to the shaft. The shaft 59 also has a wheel 63 on the end opposite the wheel 58 and it has a wrist pin 64 to which a pitman 53' is connected in order that power may be applied to both ends of the frame for imparting oscillatory motion to the said frame.

From the foregoing description and by reference to the drawing, it will be apparent that a web of material to be treated or printed is drawn from the roll 21 through 130

the printing press or mechanism and threaded through the coating means under the roller 27 and through the slot of the guide 30, the relation of parts being such that the 5 web will pass in such juxtaposition to the tapper as to be intermittently struck by the tapper as the tapper oscillates, it being understood that the tapper is oscillated by reason of its tail piece being struck by the 10 shoulders 36 as the web is being drawn. The web is interposed between the feed rolls 31 and 32, which latter is mounted on the shaft 41 in order that it may be positively driven. The shafts of the rolls 31 and 32 15 and the tapper are geared together so that they operate positively in unison, and as power is imparted to the drive shaft 56, the frame, through the connections described, will be oscillated and as the frame is oscillated, the dog 43 will impart motion to the web to project a finished card beyond the knives, it being understood that the card 20 will have reached the limit of its outward movement at the time the movable knife is approaching the stationary knife, this timing of the feed and the movement of the cutting mechanism being one that will be understood by those skilled in the art.

After the card is severed from the web 25 in its coated state, it is subjected to a baking process through the employment of a conveyer and an oven, which conveyer should be located in such relation to the cutting device as to receive cards which drop from the web as they are severed.

The conveyer and baking device or oven of the present invention includes any suitable frame 63' having drums 64' and 65 journaled at its ends, over which a wire 30 mesh conveyer belt 66 is operated. It has been found in practice that owing to the character of the wire mesh, the belt does not run straight at all times, but has a tendency to creep axially of the drum.

The creeping action is supposed to be due 45 to the unequal tension strength of the belt throughout its width and in order to guard against such creeping, one or more guide rollers 67 may be journaled on vertical axes 50 such as 68 located near the edge of the conveyor belt and on the side toward which the belt is creeping, and this arrangement has been found to hold the belt against undue lateral movement. The belt operates 55 through an oven which may be suitably encased, but which preferably has a structure comprising a plurality of side posts 69 and upper and lower transversely disposed plates 70 and 71, respectively, that constitute supports or anchorages for the top and bottom walls 72 and 73, respectively. The top and bottom walls may be of any heat 60 resisting or refractory material such as asbestos and they constitute bases on which 65 the heating elements are installed.

It has been found in practice that the degree of heat effective to produce the best results in fusing, melting or otherwise treating the deposits used in embossed printing is apt to scorch the card when subjected to the heat for the desired length of time to produce the best results, and therefore, the applicant has provided an oven having zones of relatively intense heat and a zone of relatively low temperature in order that the 70 card may be subjected to the relatively great heat at first for a short time, then maintained in a zone of less heat, and then again subjected to a zone of relatively great heat, from which it is carried by the conveyer. 75 To the end just described, the elements 72 and 73 constitute bases on which appropriate fittings or terminal plates 74 may be secured, the same being arranged as separate units on each side of the bases and having 80 suitable terminals to which resistance elements 75, in the nature of wire, may be connected in a manner to permit current to be supplied to the group of resistance elements at one end of the furnace, or to the group 85 at the other end of the furnace, or to the groups simultaneously. Furthermore, each resistance element is a unit of comparatively short length extending from one plate to the other, and if any one of the 90 short lengths becomes impaired, it can be renewed without excessive cost.

The wiring diagram is shown in Fig. 6 and a description of the same is believed 95 to be unnecessary to an understanding of the arrangement, it being sufficient to say that suitable switches 76 are provided for controlling the circuits.

As the upper and lower walls of the furnace carry heating units, the cards will be 100 subjected to heat from above and beneath and such heating also adds to the efficiency of an oven intended to treat deposits for embossed printing, but in order to maintain the conveyer in such relation to the heating devices as will cause a uniform action on the 105 cards, the conveyer is guided within the furnace on cross bars 77 which are somewhat similar to the cross plates 70 and 71, except that the cross bars have convex upper surfaces to minimize the friction between the conveyer belt and the said bars. Preferably the space between the conveyer and the upper 110 heating elements is slightly greater than the distance between the conveyer and the lower heating elements, as this will allow for any 115 distortion of the card or material as it is being carried by the conveyer. When cards and the like are heated, they have a tendency to curl or bend, so that by the relation of parts just indicated, a greater clearance will be above the conveyer in order that even if they become distorted, they will not come in contact with the heating elements. The 120 presence of the lower heating element mini- 125 130

mizes the curling action or distortion of the cards in order that if the heat is properly regulated, there is little danger of undue missshaping of the cards.

6. Power may be applied for operating the drums in any convenient manner, but as here shown, a shaft 78 has a pulley 79 secured on it, which may be engaged by a belt or other driving means, the said shaft 78
 10 having a pinion 80 engaging a gear wheel 81 on a stub shaft 82. The gear wheel 81 is connected to a pinion 83 on the stub shaft for the purpose of driving the same, and the pinion 83 meshes with a gear wheel 84 on the shaft 85 of the drum 65. Of course, other means may be provided for operating the conveyer, and the inventor does not wish to be limited with respect to the same.
- It is the purpose of the inventor to have
 20 the arrangement such that his switches will deliver current to the heating agents in a manner to produce heat at the upper and lower zones of the furnace at high and low temperatures or when the heat is increased
 25 or diminished and, of course, in the event that other heating agencies are employed, he would provide for heating both the upper and lower zones at about or approximately the same temperature in order that the heat
 30 under the conveyer and the heated zone above the conveyer would be approximately the same, regardless of whether the heat was increased or diminished.

I claim:

- 35 1. In an embossed printing machine, a multicolor printing means, means for drawing a web of material to be printed in a step by step motion through the printing means, a coating device interposed between the
 40 printing means and the drawing means through which the web is moved for receiv-

ing deposits, and means for cutting appropriate lengths from the web.

2. In an embossed printing machine, a printing mechanism, means for drawing a web of material to be printed therethrough in a step by step motion, a web coating device through which the printed web is drawn, and means to which the web passes from the coating device for cutting the web between each successive movement.

3. In an embossed printing machine, a printing mechanism, means for drawing a web of material to be printed therethrough in a step by step motion, a web coating device through which the printed web is drawn, said coating means comprising a receptacle having an end with a slot between the end and the bottom of the receptacle, means for guiding the web in proximity to the said bottom in its movement in the receptacle, an elevated guide through which the web is directed, a tapper operative to impart vibratory motion to the web in its passage from the first mentioned to the second mentioned guiding means, and means for cutting the web between each successive movement.

4. In an embossed printing machine, a multicolor printing means, means for drawing a web of material to be printed in a step by step motion through the printing means, a coating device interposed between the printing means and the drawing means through which the web is moved for receiving deposits, means for cutting appropriate lengths from the web, a furnace having a conveyer to which the severed portions of the web are delivered for movement through the furnace, said furnace having heating units above and below the conveyer, and means for controlling the heating units.

SAMUEL MARANS.
